UNITED STATES PATENT OFFICE.

ALBERT HAMILTON EMERY, OF STAMFORD, CONNECTICUT.

TRACK-SCALE TEST-CAR.

1,124,217.

Specification of Letters Patent.

Patented Jan. 5, 1915.

Application filed April 8, 1914. Serial No. 830,484.

To all whom it may concern:

Be it known that I, ALBERT HAMILTON EMERY, a citizen of the United States, residing at Stamford, in the county of Fairfield and State of Connecticut, have invented certain new and useful Improvements in Track-Scale Test-Cars, of which the following is a specification.

My invention relates to a railroad car, carrying standard weights and apparatus for handling and placing said weights on the various sections of the scale.

My invention is illustrated by four figures on two sheets of drawings, of which—

Fig. 1 shows a longitudinal section of the car containing the weights, truck, etc., in place for transportation, and also shows, in dotted lines, the projected position of the crane-bridge and the hoist and also the truck, with a weight thereon, in position on the track at the end of the car where they have been placed by the crane. Fig. 2 shows an end view of the car, weights, truck, crane and hoist with the car end-doors removed. Fig. 3 is an end view of one of the standard weights to a larger scale to show the locating and holding-down devices. Fig. 4 is a detail of one of the locating plugs and the seat therefor.

My invention is more fully described in the following specification, in which the same numerals in the various figures refer to the same parts.

1 is a complete railroad car of ordinary construction here shown with one end closed, while the other end is provided with doors 2.

3 are two rectangular bars or rails running longitudinally of the car for a portion of its length and fastened to the car floor by lag screws 4 as shown in Fig. 3. A crane-bridge composed of two channel-beams 5 and cross beams 6 and cross braces 6^a, is carried in the upper part of the car on the two wheels 7 at the front of the car and the two wheels 8 near the center of the car. The two wheels 7 are carried by the brackets 9 which are carried in turn by a steel framework secured to the frame of the car, while the wheels 8 are carried on the brackets 10 secured to posts 11 secured at their lower ends to the weight beams 3. In Fig. 2, a portion of one of the brackets 9 is removed to show parts behind it.

The crane-bridge is moved longitudinally by the screw 12, through nut 13 fastened to one of the channels 5, the screw 12 being

fastened through a suitable thrust bearing to the end of the car frame. This screw could be rotated by gearing and hand power, but I prefer to drive it by an electric motor 14, through gears on the motor shaft and screw. The hoist 15 runs in this crane-bridge, the wheels of the hoist running on the tracks 16 fastened to the lower flanges of the channel-beams 5. This hoist is provided with an electric motor for moving it along the crane-bridge and a second motor for raising and lowering the lifting hook.

The weight carrying truck 17 is provided with a motor 18 which rotates a shaft 19 provided with a worm working on a worm-wheel connected by gearing to the axles of one pair of the truck wheels, so that the truck can be moved along the track by an electric current transmitted to the motor 18 through a flexible cable. The electric power is generated by a generator 20 which may be of any desired form, such for instance as a kerosene, oil or gasoline engine driving an electric generator.

21 are locating plugs which are screwed into the track 3 and also into the tops of the weights 22. These plugs have two functions; one of providing a quick method of locating the weights in position by the conical part of the plug catching the conical part of the seat as the weight is lowered to position, causing the weight to swing to a position such that the cylindrical part of the plug enters the cylindrical portion of the seat; the other function being that of holding the weights from shifting as the car is bumped or jerked. This latter function is supplemented by the bolts 23 which keep the weights from lifting off their seats.

This apparatus is used in the following manner. The car is put in position with its end doors near one end of the scale to be tested, the end doors opened, the hold-down bolts 23 removed from the weights and the generator started. Then the crane-bridge is projected out of the car by the motor 14 through the screw 12 and nut 13. After the bridge is projected, the electric hoist is run into position over the truck which is lifted and carried out of the car and lowered onto the track. The truck is then run onto the scale and weighed by the scale. Most track scales have four pairs of primary levers and the truck should be weighed when placed over each pair. The weight of the truck being known, the accuracy of the

scale under this amount of load is determined. The truck is then run back to the position shown and one or more weights placed upon it and the scale tested with 5 various loads in a similar manner.

The truck frame is provided with locating plugs so the weights can be exactly located thereon easily. The upper faces of the weights are also provided with locating 10 plugs so that the weight can be easily and safely stacked. After the scale is tested, the weights and truck are replaced in the car and bolted down, the crane-bridge drawn in and the car closed for transportation.

15 I claim:—

1. A railroad track-scale test-car, comprising a car adapted to travel on the track of which the scale forms a part, ways in said car for receiving and supporting standard weights, and a crane-bridge having means for raising and lowering the weights and traversing said weights on the crane-bridge longitudinally of the car; said crane-bridge being bodily adjustable in the direction of its length, from a position within the car to a position overhanging the track beyond the end of the car.

2. A railroad track-scale test-car, comprising a car adapted to travel on the track 30 of which the scale forms a part, ways in said car for receiving and supporting standard weights, and a crane-bridge having a trolley-hoist running longitudinally thereon and operable for raising and lowering the 35 weights, and traversing said weights on the crane-bridge longitudinally of the car in any and all positions of the crane-bridge; said crane-bridge being bodily adjustable in the direction of its length, from a position within 40 the car to a position overhanging the track beyond the end of the car.

3. A railroad track-scale test-car, comprising a car adapted to travel on the track of which the scale forms a part, ways in

said car for receiving and supporting standard weights, having positioning means adapted to engage and release the weights by vertical movement of the weights, and a crane-bridge having means for raising and lowering the weights relatively to the positioning means, and traversing said weights on the crane-bridge longitudinally of the car; said crane-bridge being bodily adjustable in the direction of its length, from a position within the car to a position overhanging the track beyond the end of the car. 45 50 55

4. A railroad track-scale test-car, comprising a car adapted to travel on the track of which the scale forms a part, ways in said car for receiving and supporting standard 60 weights, having positioning means adapted to engage and release the weights by vertical movement of the weights, a crane-bridge having means for raising and lowering the weights relatively to the positioning means, 65 and traversing said weights on the crane-bridge longitudinally of the car; said crane-bridge being bodily adjustable in the direction of its length, from a position within the car to a position overhanging the track beyond the end of the car, and a wheeled truck having means for fixing it against horizontal movement within the car, and engaging with and releasing from the same by vertical movement; said truck being constructed to be transferred by the raising and lowering means, from within the car to a position upon the track beyond the end of the car; said truck being adapted to receive and traverse the weights over the scale. 70 75 80

The foregoing specification signed at Stamford, Connecticut, this 18th day of March, 1914.

ALBERT HAMILTON EMERY.
